(57) CLAIM

The ornamental design for a support table, as shown and described.

DESCRIPTION

FIG. 1 is a front right perspective view of a support table according to the new design;

FIG. 2 is a rear left perspective view thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a top view thereof;

FIG. 8 is a bottom view thereof; and,

FIG. 9 is a front right perspective view thereof with the environment removed.

The broken lines in the drawings illustrate portions of the environment and form no part of the claimed design.

1 Claim, 7 Drawing Sheets
